OIL BURNING STOVE

Charles J. Kessler, Cleveland Heights, Ohio, assignor to Perfection Stove Company, Cleveland, Ohio, a corporation of Ohio

Application November 8, 1935, Serial No. 48,849

5 Claims. (Cl. 126—45)

During a period at the beginning of operation of certain kinds of oil burning stoves, especially cook stoves and ranges wherein tubular burners are employed, the flame gradually increases in size as combustion progresses with the result that a much higher and therefore hotter fire ensues than originally intended and actually attained by the initial wick adjustment.

This difficulty arises from an excessive heating 10 of the burner body, and in some instances of the adjacent part of the oil supply pipe, which causes the oil contained in these parts to become elevated in temperature and therefore more volatile with the consequence that upon reaching the 15 zone of combustion it vaporizes more readily than at the start of combustion and affects the flame in the manner stated.

Aggressive manufacturers of oil burning stoves of the class referred to, catering to the popular 20 demand for cook stoves and ranges of the modern cabinet type are enclosing the burner compartments, and this construction aggravates the above mentioned difficulty.

It is the fundamental purpose of my invention 25 to eliminate this evil of growing fires in stoves of the aforesaid class. To this end, I provide a so-called burner plate or baffle, having an opening 30 for the accommodation of each burner, and arrange the same horizontally adjacent the top of the burner body so that the major portion of the burner below the zone of combustion is protected from the heat given off by the parts in and above said zone. This arrangement also results in the oil supply pipe being kept relatively 35 cool because of the fact that it is located adjacent the bottom of the burner.

While the invention is especially advantageous in oil burning cook stoves or ranges of the enclosed or cabinet type, it has marked utility in 40 connection with the earlier types of stoves and ranges in which the burner compartment is open.

It is found that the invention, which also involves certain improvements in the air controlling 45 and directing means of burners of the type referred to, overcomes, to a considerable degree at least, fluctuations of the flame due to sudden drafts caused, for example, by the opening or closing of a door in the general locality of the 50 stove, or a gust of wind blowing through the room, or something else happening to create air disturbances or eddies in the vicinity of the burner.

In the accompanying drawings, wherein similar 55 reference characters designate corresponding

parts throughout the several views, Fig. 1 is a front elevation, with parts broken away, of an oil burning cook stove embodying the invention; Fig. 2 is a vertical section substantially on the line 2—2 of Fig. 1, the burner being shown in elevation; Fig. 3 is an enlarged fragmentary sectional front elevation of the burner and the adjacent part of the burner plate or baffle, and Fig. 4 is a similar sectional plan on the line 4—4 of Fig. 3, the parts within the inner wick tube being 10 omitted.

The cook stove herein illustrated is of the enclosed or cabinet type and comprises ends 1 and 2, a top 3, a back panel 4, a front panel 5, and a door 6, all formed of sheet metal and suitably 15 connected together.

Guides 10, constituted of inwardly facing channel members, are horizontally disposed immediately inside each of the ends 1 and 2 with their bottom flanges slightly below the lower 20 edge of the front panel 5. A burner tray 11 is slidably supported within the guides 10 for convenient removal in a direction forwardly of the stove to facilitate cleaning, and it is prevented from excessive rearward movement when replaced by stops 12 that are struck from the webs of the guides.

The lower edge of the rear panel 4 is in substantially the horizontal plane of the upper edge of the front panel 5 and extending from one to 30 the other is the burner plate or baffle 15. One end of the plate or baffle joins the stove end 2, while its opposite end, in the present construction, joins a partition 16 that, with the end 1, encloses a space for a reservoir 17 for liquid fuel. 35 The burner plate or baffle 15 has an opening 18 for each burner 20, said opening being surrounded by an upstanding collar 21. According to the present construction, the collar 21 is formed with a flange 22 that is engaged with the 40 underside of the body portion of the burner plate or baffle and is secured thereto by suitable means, as by welding.

Surrounding and carried by each burner body 20 a suitable distance below the upper end thereof is an annular seat 25 that supports a correspondingly shaped air controller 26 including inner and outer flanges 27 and 28, respectively, the latter being curled outwardly at its lower end and fitting within the depressed portion of the seat 50 25. The bottom of the seat 25, inwardly of said flange 28, has a series of large openings 29, only enough metal being left between the openings to form radial spokes 30 of requisite strength. The flange 28 is also provided with a series of open- 55

ings 31, the same being arranged with their lower edges in substantially the plane of the upper edge of the seat 25, and immediately above the openings 31 the flange is reduced in diameter to form a ledge 32 on which a burner drum or chimney 35 rests.

The burner body is of the usual construction comprising inner and outer tubes that are connected together at their lower ends and are spaced apart radially to enclose between them an annular space for a cylindrical wick 40 whose upper end operates between the corresponding ends of said tubes. A flame spreader 41 of usual character is suitably supported within the upper end of the 15 burner body.

Oil from the reservoir 17 is conveyed by a pipe 45 to each of the burners 20, communication between the burner and pipe being effected through a fitting 46, in the common and well known manner. Each burner is thus connected to and supported from the pipe 45 on one side, and on the other by a member 47, usual in burners of this character. Above each burner the top 3 has an opening 50 fitted with a grid 51.

Access to the burners for lighting, cleaning and adjusting purposes is had through the door 6 which is shown as connected at its lower edge by hinges 52 to the upper edge of the front panel 5 and as equipped adjacent its upper or free edge with a handle 53. When the door 6 is open, the drum or chimney 35 of each burner may be tilted rearwardly until its upper end contacts a bracket 55 that is connected to and extends forwardly from the back panel 4, and the air controller 26 and the bottom portion of the drum or chimney 35 are so constructed and related that as the drum or chimney swings rearwardly it imparts a like movement to the air controller, the latter rocking at its rear edge upon the seat 25, as illustrated and described in Chadwick and Kessler Patent No. 1,944,492, dated January 23, 1934. The essential purpose of the previously mentioned collars 21 is to provide clearance for the drums or chimneys 35 when they are tilted rearwardly, in the manner shown in dotted lines in Fig. 2. If the collars were dispensed with, the burner plate or baffle 15 would have to be elevated to about the horizontal plane now occupied by the tops of the collars, because this relation between the burners and the top sides of the surrounding openings is essential to a proper operation of the apparatus, and with the burner plate or baffle so elevated, it would be in the way of the lower, rear parts of the drums or chimneys when the latter are tilted. On the other hand, it has been shown by experiments that to materially lower the burner plate or baffle and correspondingly lengthen the collars (it being remembered that their upper ends have to bear a given relation to the tops of the burners) adversely affects the action of the burners. Obviously, a further purpose served by the collars 21 is to impart rigidity to the burner plate or baffle in the region of the burner openings and prevent warping or distortion thereof.

When a burner is in operation, air, by thermal action, rises through the opening 18. This air is drawn from the space below the burner plate or baffle which is open at the back. The air, for this reason being fresh and cool, maintains the temperature of the lower portion of the burner body relatively low, although this result is practically assured by the fact that said portion of the burner body is positively shielded from the heat given off by the drum or chimney 35 and the parts

in the region of the zone of combustion. In this connection, it may be explained that by reason of the character of the oil feed employed in this class of stoves, the oil level in the burner bodies is a material distance below the upper ends of the burner tubes wherefore the oil contained within the burner body and that present in the adjacent portion of the feed pipe 45 is kept cool, avoiding the difficulty hereinbefore described of growing fires.

As usual in burner drums or chimneys of the sort shown, the annular bottom wall is provided with a series of air admitting openings 36; and in the construction illustrated, an annular deflector 37 extends inwardly from the peripheral wall of the drum above said openings toward and below the upper end of the air controller 26, this deflector serving to smooth out the jets of air rising through the openings 36 into a continuous sheet that hugs the air controller and is spread by the flaring upper end thereof toward the wall of the drum or chimney adjacent which it rises. A part of the air that is drawn upwardly through the baffle collar 21 enters the bottom of the air controller 26 through the large openings 28 in the seat 25 and this column of air, thus supplied to the air controller, is divided into two parts by the flange 27, one part passing upwardly through the air controller, while the other part escapes through the openings 31 and enters the drum or chimney 35 through the openings 38. Without the openings 31, the drum is deprived of the requisite amount of air as that rising about the seat 25 is in most part deflected away from said openings by the flared upper end of the seat.

With the burner so well protected by the burner plate or baffle, in the vital region of its air controlling parts, its action is little if any affected by air disturbances or drafts which cause similar burners not so protected to momentarily flare and smoke, or in the case of a low fire, to go out.

Having thus described my invention, what I claim is:

1. In a stove of the class described, a burner body, an air controller surrounding the upper end of the burner body, said controller having a circumferential chimney supporting ledge and a series of openings therebelow, a chimney resting with its lower end upon said ledge, a flange inside the air controller spaced inwardly from the aforesaid openings thereof, said flange serving to deflect a part of the air rising through the air controller inwardly adjacent the top of the burner and a part outwardly through said openings of the air controller, a baffle provided with an opening, and an upstanding collar surrounding the opening the internal diameter of which is materially greater than the external diameter of the air controller, the baffle being arranged horizontally and the air controller being disposed within the collar with its chimney supporting ledge substantially above the plane of the upper end thereof.

2. In a stove of the class described, an enclosure comprising a top, ends, a rear panel and a front closure, a burner plate constituting the bottom of said enclosure, said plate having an opening, an upstanding collar surrounding said opening, a burner body arranged with its upper portion within said collar and its top a substantial distance above the corresponding end of the collar, the internal diameter of the collar being materially greater than the external diameter of the burner body, and a chimney supported above and in operative relation to the burner

body, the top having an opening above said chimney and the chimney being of considerably greater diameter adjacent its lower end than the burner body and being tilttable with respect to said body.

5 3. In a stove of the class described, an enclosure comprising a top, ends, rear panel, and a front closure, a burner plate constituting the bottom of said enclosure, the same having an opening, an upstanding collar surrounding said opening, a burner disposed with its upper portion within said collar and its top a substantial distance above the corresponding end of the collar, a seat surrounding the burner body adjacent its upper end and contiguous to the upper end of said collar, the internal diameter of the collar being materially greater than the external diameter of said seat, an air controller on said seat, and a chimney resting upon the air controlling member and tilttable therewith upon the seat.

20 4. In a stove of the character described, a hori-

zontally disposed baffle having an opening, a burner of considerably lesser diameter than said opening supported independently of, and out of contact with the baffle, with its upper end portion in said opening and its top a substantial distance 5 above the plane of the baffle, and a chimney independent of the baffle and removably supported thereabove by the burner.

5. In a stove of the character described, a horizontally disposed baffle having an opening, an 10 upstanding collar surrounding said opening, a burner of considerably lesser diameter than the internal diameter of said collar supported independently of the baffle with its upper end portion disposed within, and out of contact with, 15 the collar while its top is spaced a substantial distance above the top edge of the collar, and a chimney surmounting the burner and tilttable with respect thereto.

20
